UNITED STATES PATENT OFFICE.

ELIAS H. HERSCHEY, OF LANCASTER, PENNSYLVANIA.

MEANS FOR PRESERVING WOODEN POSTS AND POLES FROM DECAY.

1,293,771.

Specification of Letters Patent. Patented Feb. 11, 1919.

Application filed February 14, 1918. Serial No. 217,074.

To all whom it may concern:

Be it known that I, ELIAS H. HERSCHEY, a citizen of the United States, residing at Lancaster, in the county of Lancaster and State 5 of Pennsylvania, have invented certain new and useful Improvements in Means for Preserving Wooden Posts and Poles from Decay, of which the following is a specification.

The object of this invention is to preserve 10 more perfectly and certainly than heretofore against decay the buried butts or lower ends of wooden posts and poles. To this end I provide an annular space or chamber for preservative fluid in the casing which surrounds as usual the butt of the post, said chamber being preferably divided into compartments by vertical ribs so that the post will fit tightly on all sides against said ribs, yet be in contact on all sides with the said preservative fluid. I also provide for shielding 15 this space or chamber against the intrusion of rain or other moisture or foreign matter from above by fitting an annular cap over said chamber and into an annular groove of the post or pole; and provide the latter with holes for the reception of said fluid from said chamber and with other holes or channels and means of liquid supply whereby such liquid may be directed into said chamber 20 without removing said cap and from a point or points above the latter. The ribs aforesaid are also provided with transverse perforations to allow said liquid to flow from one compartment of said chamber into another, thus keeping up the supply of the 25 entire chamber. Furthermore the production of said chamber and ribs in casting said chamber of concrete is preferably effected by fastening detachable vertical strips 30 to the lower part of the pole with slight intervals between them, before casting, the intervals providing the ribs and the strips providing the alternating compartments, said strips being removed after casting, and 35 the means of attaching the strips being used for supporting the capping.

In the accompanying drawings Figure 1 represents a vertical section partly in elevation of the lower part of a pole or post and 40 its casing;

Fig. 2 represents a cross section on the line 2-2 of Fig. 1;

Fig. 3 represents a detail elevation of the 45 lower part of the pole, showing its groove and holes, with casing and cap in section;

Fig. 4 represents an enlarged detail view of two of the ribs of the casing, showing the perforations distinctly;

Fig. 5 represents a view of the pole similar 60 to that in Fig. 3 but with the strips attached, before casting the casing.

A designates a pole or post, B, its cement or concrete casing, C, an annular space or chamber in the inner face of said chamber, 65 surrounding the post, so that any preservative liquid or semi-liquid contained therein will be in contact with said pole. This chamber is approximately on the ground level O, but extends more or less above and 70 below the latter. It is divided into compartments by vertical ribs D, which contact with the pole or post on all sides of it, making a tight joint and bracing it everywhere, though permitting access of the preservative liquid, to said pole on all sides thereof. Each rib is transversely perforated 75 at d, so that the fluid will flow from compartment to compartment, filling the entire chamber as also over the tops of the ribs. 80 Holes a are bored into the sides of the post, for admission of such liquid into its interior from said chamber. The upper end or top of the chamber is shielded against rain, snow or any other foreign matter by an annular 85 waterproof cap F which fits into an annular groove G of the said post and has soft packing f under it in contact with the top of the casing and securely fitting the upper end of said chamber. Liquid may be supplied to said chamber, without removing 90 said cap, by means of one or more tubes or liquid containers H, communicating with inclined and bent channels I in said pole, having their upper ends above said cap and at 95 the exterior of said pole whereas their lower ends are below said cap and discharge into said chamber. The said tubes cups or containers H, may be screwed into the upper ends of said channels or attached in any 100 other way. Said tubes may be of any convenient form. Any form of such article may be employed.

The readiest way to make the chamber C divided by ribs D is to removably attach 105 strips K Fig. 5, to the corresponding part of the pole, cast the cement casing on this part of the pole thus provided and withdraw said strips after the cement hardens. Each strip will thus leave one of the compartments of 110 the chamber C behind it and the intervening

mainder of the commutator structure and that provides a long creepage path between said segments and said supporting structure.

2. In a commutator cylinder, the combination with conducting and insulating segments and a supporting V-ring therefor, the said segments projecting beyond the end of said V-ring, of an insulating member located within the annulus formed by the projecting portions of said segments, said insulating member having an inwardly projecting flange to provide a comparatively long creepage path between said segments and said V-ring.

3. In a commutator cylinder, the combination with conducting and insulating segments and a supporting V-ring therefor, the said segments projecting beyond the end of said V-ring, of an insulating member located within the annulus formed by the projecting portions of said segments and having an inwardly projecting flange spaced from said V-ring.

4. In a commutator cylinder, the combination with conducting and insulating seg-

ments and a supporting V-ring therefor, the said segments projecting beyond the end of said V-ring, of an insulating member secured to the face of said V-ring and having a portion thereof projecting inwardly beyond the inner surface of said V-ring.

5. In a commutator cylinder, the combination with conducting and insulating segments, of a cylindrical supporting structure therefor, said segments projecting beyond the end of said supporting structure, and an insulating member located within the annulus formed by the projecting portions of said segments, said insulating member having a tapering portion adapted to exert a wedging force against said segments, and also having an inwardly projecting flange that is spaced from the remainder of the commutator structure and that provides an extended creepage path between said segments and said supporting structure.

In testimony whereof, I have hereunto subscribed my name this 22nd day of Sept., 1916.

RUDOLF E. HELLMUND.
